BEDSPRING

Don Carlos Travis, Kenosha, Wis., assignor to
Simmons Company, New York, N. Y., a corpora-
tion of Delaware

Application February 11, 1935, Serial No. 5,992

13 Claims. (Cl. 5—267)

This invention relates to improvements in bed springs and more particularly to a top construction designed especially for use in connection with inner spring mattresses, although not restricted to association with inner spring mattresses.

The main object of the invention is to provide a bed spring construction which will afford a firm but nevertheless sufficiently resilient support for a mattress especially of the inner spring type.

Another object is to provide an improved bed spring top construction of the type referred to which may be produced economically and which will be efficient and durable in use and which will present an attractive appearance so as to facilitate the sale thereof.

Other objects and advantages of the invention will be understood by reference to the following specification and accompanying drawing wherein there is illustrated a bed spring embodying a selected form of the invention.

In the drawing—

Fig. 1 is a plan;

Fig. 2 is a section on the line 2—2 of Fig. 1; and

Fig. 3 is a perspective of a portion of one element of the improved structure.

Referring now to the drawing, the improved bed spring structure therein disclosed includes a border frame 5 which may in this instance be considered as being formed of angle iron arranged with one flange disposed in a horizontal plane and another flange depending vertically from the outside edge of the horizontal top flange.

A plurality of axially vertical coil springs designated 6 are arranged around the inside of the border frame and each of such coil springs has its top coil provided with a loop portion 7 which extends outwardly beneath the horizontal flange of the angle iron border frame. The loops 7 of the border springs 6 receive rivets such as indicated at 8 which are anchored in the horizontal flange of the border frame and serve to rigidly secure the top coils of the border springs 6 to said border frame. Other arrangements for anchoring the border springs 6 to the border frame may be employed if preferred. A plurality of coil springs 9 arranged within the area bounded by the border springs 6 are so disposed as to form rows aligned with oppositely disposed border springs.

In this instance, the inner coil springs 9 are so arranged as to form rows extending both lengthwise and transversely of the bed spring structure. In the present instance, the springs 9 will be referred to as forming rows extending longitudinally of the bed spring, i. e., in the direction of the greatest length of the bed spring and such longi-

tudinally extending rows are aligned, as indicated, with border springs respectively secured to the ends of the border frame. In the illustration, only one corner portion of the bed spring is illustrated but it will be readily understood that the opposite end portion will appear exactly the same as the illustrated portion except in reversed arrangement.

Each longitudinally extending row of springs has associated with it a frame or grille structure 10. Such frame structure includes a pair of flexible straps 11, 11 which are preferably of thin strap metal. Intermediate adjacent springs 9 in each row, the straps 11, 11 are connected by means of cross members such as 12, the latter having their end portions underlying straps 11 and pivotally secured thereto by means of rivets, or preferably eyelets, such as indicated at 13. The cross straps 12 thus serve to hold the strap pairs 11 in predetermined spaced, substantially parallel relation.

The straps 11, 11 of each longitudinally extending spring row, overlie opposed side portions of the top of the spring row and said straps are formed with portions designated 14, 14 bent downwardly so as to embrace underlying side portions of the top coils of the respective springs 9. The downwardly bent portions 14, 14, as best shown in Fig. 2, form inverted U-shape portions which embrace the side portions 15 of the top coil springs 9. At the lower edges of the downwardly bent or leg portions of the inverted U-shaped formation, there are formed outwardly extending ledges 16, 16 and the portions 14, 14 are provided with elongated openings or slots 17 which are located intermediate the respective ledges 16 and the plane of the bottom surfaces of the coil portions 15. By reference to Fig. 3, it will be seen that the described inverted U-shaped formation is produced by merely stamping the straps 11 and 11 without cutting or otherwise materially weakening the same. The inverted U-shaped portions of the straps become rigid and relatively inflexible and are proportioned to snugly fit the opposite side portions of the top coils of the spring 9, 45 so that the straps 11, 11 will be firmly and accurately positioned with respect to the adjacent springs 9 in each row.

For anchoring the top coil portions 15 in the U-shaped portions of the straps 11, there are provided anchoring straps 18 which extend transversely of the rows substantially diametrically of the respective springs of each row. The said anchoring straps 18 extend through the openings 17 in the inverted U-shaped portions of the straps 55

11 so as to be interposed between the spring portions 15 and the said ledges 16, thereby locking the spring portions 15 in the housing formed by said U-shaped portions of the straps 11. To prevent displacement of the anchoring straps 18, the end portions 19 thereof are bent downwardly and inwardly around the respective outermost ledges 16, as clearly shown in Fig. 2. Such bending of the ends of the straps 18 may easily be accomplished manually and it may be facilitated by providing holes 19a in the ends of the straps in the zone of bending thereof. The anchoring straps 18 thus not only serve to lock the coil springs to the straps 11, but also to prevent 15 spreading thereof.

The straps 11 which overlie adjacent marginal portions of adjacent spring rows are resiliently connected together by means of helical springs 20, 20 of suitable length and formed with hooks 20 which may conveniently be engaged with the eyelets or tubular rivets 13, 13.

The ends of each of the straps 11 are resiliently connected by means of helicals such as indicated at 21 with the border springs 6 which are aligned with the respective rows, the top coils of such aligned border springs being preferably formed with ears or loops 22 which facilitate the connection of the springs 21 to said border springs 6 and serve to maintain said helicals 21 in pre-determined position substantially in axial alignment with the lengths of the marginal straps 11. As indicated, the helicals 21 are provided with hooked ends which engage the ears 22 of the border springs 6 and which engage suitable openings, such as indicated at 23, in the adjacent ends of the straps 11.

The cross members 12 of the outermost rows of springs 9 are provided with outwardly projecting end extensions 24 and said extensions are 40 provided with openings indicated at 25. Helical springs 26 provided with hooks at their opposite ends are stretched between the end extensions 24 of the cross straps and adjacent side border springs. Since the cross straps 12 are located 45 intermediate the springs of each row, it is convenient to connect the sides of the outermost rows to the side border springs by means of coil springs 26 arranged in pairs, the springs of each pair being arranged in diverging relation, 50 as shown.

Any suitable form of body support may be provided. Inasmuch as the present invention is concerned only with the top construction, no bottom structure is illustrated but it will of course be understood that there is associated with the border frame 5 a main supporting base frame which carries suitable cross straps or other means for supporting the lower ends of the coil springs 6 and 9.

The described structure may be advantageously used in combination with inner spring mattresses, especially for the reason that ample top surface area is provided to adequately support the springs of an inner spring mattress. Because of the comparatively small spaces intervening between adjacent portions of the various straps, it is not possible for the springs of an inner spring mattress to become displaced because of lack of support. Although there is adequate support 65 provided as explained, the bed spring is nevertheless resilient so as to avoid impairment of the comfort qualities of an inner spring mattress. The straps 11 being flexible metal straps, permit localized bending to conform to localized 70 weights applied to the bed spring, and inasmuch 75

as the rows of springs 9 are resiliently supported by means of the connecting helicals 20, 21 and 26, they may shift transversely or longitudinally or in a lateral direction, as may be required, as an incident to localized compression of the mattress. The metal strap elements 11, 12 and 18 are of sufficiently strong but quite thin material so as to avoid the addition of an objectionable amount of weight to the bed spring structure. All of the said elements are to be understood as 10 being of sufficient flexibility to permit bending and yielding under the application of localized pressures.

Changes in the described structure may be made without departing from the spirit of the 15 invention, the scope of which should be determined by reference to the following claims, the same being construed as broadly as possible consistent with the state of the art.

I claim:

1. In a bed spring, a plurality of axially vertical coil springs arranged in a row, a pair of elongated, substantially parallel, relatively flexible straps respectively overlying the marginal side portions of the top of the row and each anchored to a portion of each spring in the row, and means comprising a plurality of spaced, short straps extending transversely of said row intermediate said springs and anchored at the ends thereof to said elongated straps to maintain the same in 30 said substantially parallel relation.

2. In a bed spring, a plurality of axially vertical coil springs arranged in a row, a pair of elongated, substantially parallel, relatively flexible straps respectively overlying the marginal 35 side portions of the top of the row and each anchored to a portion of each spring in the row, means comprising a short strap extending transversely of the row over each spring and anchored at the ends thereof to said elongated straps to 40 maintain the latter in operative relation to the springs, and means comprising other short straps anchored at the ends thereof to said elongated straps intermediate adjacent springs to maintain the same in said parallel relation.

3. In a bed spring, a border frame, a plurality of axially vertical coil border springs respectively disposed adjacent said border frame and having their top coils anchored to said border frame, a plurality of axially vertical coil springs arranged in rows aligned with oppositely disposed border springs, strap means forming a grille, said grille being disposed over the top of one of said rows of springs and secured thereto, and means resiliently connecting the opposite ends of said 55 grille to said oppositely disposed border springs.

4. In a bed spring, a plurality of axially vertical coil springs arranged in a row, a pair of substantially parallel, elongated, relatively flexible straps respectively overlying the marginal 60 side portions of the top of the row, said elongated straps each having opposed marginal portions bent to embrace portions of the top coils of said springs underlying the strap portions intermediate said opposed marginal portions, means connecting the bent marginal portions of said straps below the embraced coil portions to anchor the straps to said coils, and means for maintaining said elongated straps in said parallel relation comprising a plurality of short, transversely extending straps anchored at the ends thereof to said elongated straps intermediate said springs.

5. In a bed spring, a plurality of axially vertical coil springs arranged in a row, substantially parallel flexible straps respectively overlying the 75

5 marginal side portions of the top of the row, said straps each having opposed marginal portions bent to embrace portions of the top coils of the springs underlying the strap portions intermediate said opposed marginal portions, said bent strap portions being provided with apertures extending therethrough below said top coils, and cross members extending through said apertures and having end portions bent to anchor 10 the members against displacement from said openings, said cross members serving to anchor said top coils in said bent strap portions.

6. In a bed spring, a plurality of axially vertical coil springs arranged in a row, a pair of substantially parallel flexible straps respectively overlying the marginal side portions of the top of the row, said straps each having marginal portions bent downwardly so as to embrace oppositely disposed portions of the top coils of the 20 springs between said downwardly bent marginal portions, said downwardly bent marginal portions having sidewise extending ledges formed on their lower edges and having aligned openings extending therethrough above said ledges and below 25 the embraced coil portions, and cross members extending through aligned openings of said pair of straps so as to lock said embraced coil portions to said marginal overlying straps, said cross members having end portions bent around the 30 respectively outwardly extending ledges to anchor the members against displacement from said openings.

7. In a bed spring, the combination of a border frame, a pair of axially vertical coil border springs disposed inside of said border frame adjacent opposed portions thereof and respectively having their top coils anchored to said border frame, a plurality of axially vertical coil springs arranged in a row extending between said border springs and in alignment therewith, a pair of substantially parallel flexible straps respectively overlying the marginal side portions of the top of said spring row, said straps each having marginal portions bent downwardly so as to embrace oppositely disposed portions of the top coils of the springs between said downwardly bent marginal portions, said downwardly bent marginal portions having sidewise extending ledges formed on their lower edges and having aligned 45 openings extending therethrough above said ledges and below the embraced coil portions, and cross members extending through said aligned openings of said pair of straps so as to lock said embraced coil portions to said marginal overlying straps, said cross members having end portions bent around the respective outwardly extending ledges to anchor the members against displacement from said openings, and means resiliently connecting the ends of said straps to 50 the respectively adjacent border springs.

8. In a bed spring, the combination of a border frame, a plurality of border springs arranged in spaced relation around the inside of the border frame and respectively having their top coils secured to said border frame, a plurality of axially vertical coil springs disposed in relatively spaced relation within the area surrounded by said border springs and arranged in rows respectively aligned with oppositely disposed pairs of 55 border springs, flexible strap grilles associated with the tops of each of said spring rows and each comprising a pair of flexible straps respectively overlying the marginal side portions of the top of a spring row, a cross member underlying the top coil of each spring in the row, extending transversely of the row and secured adjacent its ends to said overlying straps, said cross 60 top coils of each spring in the row, extending

transversely of the row and secured at its ends to said overlying straps, said cross member serving to lock said overlying straps and springs in assembled relation, cross members connecting said marginal straps intermediate adjacent 5 springs of the row, said last mentioned cross members of all of the spring rows being disposed in longitudinal alignment transversely of the direction of said rows, resilient means connecting adjacent ends of said aligned cross members, and 10 means resiliently connecting the ends of the overlying straps of each spring row with oppositely disposed border springs.

9. In a bed spring, the combination of a border frame, a plurality of border springs arranged in spaced relation around the inside of the border frame and respectively having their top coils secured to said border frame, a plurality of axially vertical coil springs disposed in relatively spaced relation within the area surrounded by 15 said border springs and arranged in rows respectively aligned with oppositely disposed pairs of border springs, relatively independent flexible strap grilles associated with the tops of each of said spring rows and each comprising a pair of flexible side straps respectively overlying the marginal side portions of the top of a spring row, a cross member underlying the top coil of each spring in the row, extending transversely of the row and secured at its ends to said overlying 20 straps, said cross members serving to lock said overlying straps and springs in assembled relation, cross members connecting said marginal straps intermediate adjacent springs of the row, said last mentioned cross members of all of the 25 spring rows being disposed in longitudinal alignment transversely of the direction of said rows, resilient means connecting adjacent ends of said aligned cross members, means resiliently connecting the ends of the overlying straps of each 30 spring row with oppositely disposed border springs, and means resiliently connecting the outer sides of the grilles overlying the outermost 35 spring rows to adjacent border springs.

10. In a bed spring, the combination of a border frame, a plurality of axially vertical coil springs disposed in relatively spaced relation and arranged in rows within said border frame, independent, flexible strap grilles secured to the tops of each of said spring rows and each comprising 45 a pair of spaced, relatively flexible side straps respectively associated with the marginal side portions of the top of a spring row, and cross members connecting and maintaining said straps in relatively fixed relation to each other, spring 50 means which serves to provide a resilient connection between the ends of the side straps of each grille with adjacent portions of said border frame and other spring means which serves to provide a resilient connection between the outermost 55 spring rows to adjacent portions of said border frame.

11. In a bed spring, the combination of a border frame, a plurality of axially vertical coil 65 springs disposed in relatively spaced relation and arranged in rows within said border frame, relatively independent, flexible strap grilles associated with the tops of each of said spring rows and each comprising a pair of flexible side straps 70 respectively overlying the marginal side portions of the top of a spring row, a cross member underlying the top coil of each spring in the row, extending transversely of the row and secured adjacent its ends to said overlying straps, said cross 75

- members serving to lock said overlying straps and springs in assembled relation, and means resiliently connecting the ends of the side straps of each grille with adjacent portions of said border frame.
12. In a bed spring, a frame, a plurality of axially vertical coil springs disposed within said frame so as to define a plurality of generally parallel, longitudinally extending rows, and a grille structure overlying the upper coils of each of a plurality of said rows of springs, each of said grille structures comprising a pair of spaced, generally parallel, elongated strap members which are maintained in spaced relation by short, trans-
- 15 versely extending cross straps affixed at the ends thereof to said elongated straps, said elongated straps forming a part of each of said grilles being anchored to a marginal edge portion of at least some of the springs in the row with which said
- 20 grille is associated, said grilles comprising separate, unitary structures and being resiliently connected to each other and to said frame.

13. In a bed spring, a frame, a plurality of axially vertical coil springs disposed within said frame so as to define a plurality of generally parallel, longitudinally extending rows, a grille structure overlying the upper coils of each of a plurality of said rows of springs, each of said grille structures comprising a pair of spaced, generally parallel, elongated straps which are maintained in spaced relation by short, transversely extending cross straps affixed at the ends thereof to said 10 elongated straps, said elongated straps forming a part of each of said grilles being anchored to opposed marginal edge portions of the top coils of at least some of the springs in the row with which said grille is associated by other short straps af- 15 fixed at the ends thereof to said elongated straps, said grilles comprising separate unitary structures and being resiliently connected to each other and to said frame.

DON CARLOS TRAVIS. 20
